UNITED STATES PATENT OFFICE

GEORGE W. KING, OF COFFEYVILLE, KANSAS, ASSIGNOR OF FIVE-EIGHTHS TO ROY T. OSBORN, OF BRONXVILLE, NEW YORK, AND ONE-FOURTH TO WALLACE E. BECKNER, OF COFFEYVILLE, KANSAS

FURNACE FOR STILLS, ETC.

Application filed August 4, 1928. Serial No. 297,506.

My invention relates to furnace settings for boilers, stills and the like. It is particular advantage in connection with oil stills having the usual horizontal cylindrical boiler, and is described hereinafter in relation thereto. In operating oil stills, much difficulty and trouble is experienced by reason of local overheating. Ordinarily, the flames from the fire box impinge directly on the boiler bottom and sides and, as it is impossible to evenly distribute the flames, the still is apt to become overheated in some portion of its surface, though in other portions, at the same time, it is not receiving as much heat as efficient operation demands. The oil directly over the areas so overheated is thereby subjected to destructive distillation to a much greater extent than the oil over the less heated portions of the boiler whereby carbon is caused to accumulate in the area of high temperature, and the accumulation of the carbon, which is a relatively poor conductor of heat, to an extent insulates the metal of the still from the cooling effect of the oil whereby the continued heating overheats the metal of the still to such a degree that it is apt to buckle or bulge downwardly under the weight of the oil. Furthermore, as the oil distills off and the level thereof in the still or boiler falls, the side portions of the still above the boiling liquid level and exposed to the heat are no longer subject to the cooling influence of the oil and hence they are apt to be overheated with similar injurious results. This is particularly true in running to coke, in which operation the final residue is only a relatively small proportion of the original body of oil. It is an object of my invention to provide a furnace for this purpose in which the application and distribution of the heat to the boiler or still body may be readily controlled at all times, direct impingement of the products of combustion and flame upon the boiler minimized or prevented and the heat more evenly and efficiently distributed thus largely obviating the troubles due to local overheating. It is a further object to provide for readily adjusting the degree or amount of heat applied to different areas along the still so that in the

event it is desired for any reason to increase or diminish the heating effect over one area, this may be done without substantially affecting the other areas of the boiler exposed to heat.

With this object in view, I employ a series of two or more fireboxes arranged at intervals along and beneath the boiler and mounted for independent vertical adjustment, so that they may be raised or lowered as the operating conditions from time to time may dictate to vary the heating effect on the areas immediately above the respective fireboxes, and I also provide for so controlling the outflow of gases from the heating chamber at different points along the sides of the boiler as to regulate the heat applied thereto above the level of the contents thereof.

Another object of the invention is economy in battery operation. Ordinarily, the stills of a battery are arranged side by side and so operated that they may be successively charged, fired and cleaned out for a new charge. After a run is completed, a still must be cooled down to approximately atmospheric temperature to permit the operatives to remove the coke and prepare it for a new charge. When the still is again fired, much time and fuel are consumed in heating to operating temperatures, partly because of the necessity of again heating up the fire box. My invention provides for removing the highly heated firebox or fireboxes from a still, the run of which has been completed, to a still which is ready to be fired, thus permitting a more rapid cooling of the one and obviating the necessity of heating up a firebox or fireboxes for the other.

Other features of my invention will appear from the detailed description and claims. My invention, however, is not limited to oil stills nor to the specific construction disclosed as it is intended to cover it herein as broadly as the state of the art will permit.

Referring to the drawings accompanying and forming a part of this specification:

Figure 1 is a vertical central longitudinal section through a still embodying my invention, parts being shown in elevation;

Figure 2 is a transverse vertical section 100

thereof on the plane of line 2—2 of Figure 1; and

Figure 3 is a horizontal section through one of the fireboxes on the plane of line 3—3 of Figure 2.

Fig. 4 is a diagrammatic front elevation of a battery of stills, showing a furnace being moved from one still to another.

Each part is identified by the same reference character wherever it appears in the several views.

Except in the respects hereinafter pointed out, the still or boiler 4 is or may be supported in the usual manner, at about its horizontal diameter, in a setting comprising side walls 5, front end wall 6 and rear end wall 7. The setting is formed with a heating chamber 8 which may be formed of fire brick and the bottom 9 of which is supported by beams or otherwise and formed with rectangular openings 10, 10 for the reception of the fireboxes 11, 11. Any desired number of fireboxes may be employed. The openings are of sufficient size to permit the fireboxes to be freely raised and lowered therethrough but at the same time to prevent undue passage of air therethrough around the fireboxes. Walls or pillars 12, 12 at the respective ends of the still assist in supporting it. Access to the interior of the still may be had through the tubular extension 14 thereof extending through the front wall of the furnace. A removable cover 15 is applied to the end of the extension.

The fireboxes 11, here shown as two in number, may be made of fire brick or any suitable heat-resisting material with proper reinforcing. They are shown as rectangular, comprising side walls and bottoms and the tops thereof are composed of brick checker work 17 supported on the walls of the fire box and on arches 18 extending between the side walls of the firebox and suitably spaced to permit the passing of the products of combustion between them. Burners 19, of which four are shown for each firebox, project through the side walls thereof and are connected to burner pipes 40. The burners are supplied with fuel gas from two pipes 20 arranged in recesses in the inner sides of the respective side walls of the setting and connected to the burner pipes 40 by articulated or flexible pipes 21. The pipes 21 are so connected to the burner pipes, by couplings or otherwise, that they may be readily disconnected therefrom.

Each firebox is mounted on a carriage 22 provided with wheels 23, for a purpose which will appear.

The furnace setting is of sufficient height to provide a chamber 28 beneath the floor of the heating chamber into which the fireboxes may be lowered and chamber 28 is formed with an opening or doorway 27

through which the fireboxes may be removed and inserted.

For raising, or lowering and adjusting, the fireboxes, a pair of hydraulic cylinders 24, 24 may be employed, the piston rods of which carry at their upper ends crossheads 25, shown in elevated position in full lines and in lowered position in dotted lines in Figure 1, the opposite ends of which are notched at 26 to receive the axles of the wheels 23 of the firebox carriages.

The floor 29 of chamber 28 is provided with a pair of rails 30 which, preferably, extend through the opening 27. The construction is such that the fireboxes on their carriages can be run onto the rails and so located with respect to the hydraulic cylinders that the axles of the wheels 23 will overlie the notches 26 in the crossheads on the hydraulic cylinder plungers. Thus, when a crosshead rises it will carry with it the carriage and firebox located above it, lifting them from the rails and raising the firebox to proper position within the heating chamber. The articulated supply pipe or pipes may then be coupled to the burners.

In usual refinery practice the stills are arranged in batteries of a number of stills arranged in a row parallel to each other. After the distillation of a charge is completed it is necessary to let the still cool down after which the coke or other residue is discharged from a still before it is again charged. I arrange a car 31 on tracks 32 extending along in front of such a battery of stills, the car being provided with a pair of tracks 33 extending transversely to the path of movement of the car and at such height that they may be brought into registry with any of the tracks 30, above-mentioned, of the respective furnaces of the battery. When a distilling operation in one still of the battery is completed, the fireboxes, which have been furnishing the heat therefor, may be disconnected from the fuel pipes 20, lowered by the hydraulic means described until the wheels of the carriages rest on the tracks 30, run onto the tracks 33 of the car 31 and transferred to another still of the battery which has previously been charged and is ready for operation, as shown in Fig. 4. As the fireboxes with their checker work have considerable heat-storing capacity, there is thus transferred to the new distilling operation a large amount of heat remaining in the fireboxes from the finished operation, thus saving the time which would otherwise be necessary to heat up the fireboxes and the fuel which otherwise would be spent for this purpose. Furthermore, the removal of the hot fireboxes permits the still to cool off more rapidly. The fireboxes are of sufficient size to furnish ample combustion space and the checker work prevents direct impingement of the flames on the boiler and, because of its heat-storing

capacity, permits more even heating. By reason of the confined combustion chamber, the firebox may be quickly heated up to a temperature at which all smoke is consumed.

5. Moreover, the fireboxes may be readily adjusted toward and from the boiler, independently of each other, as operating conditions demand.

Side flues 34, at suitable intervals in the 10 side walls of the setting, at their upper ends, as at 35, open into the heating chamber on opposite sides of and adjacent to the plane of support of the boiler. At their lower ends, the side flues open into stack flues 36 leading 15 to stack 37. Dampers 38 in the respective side flues control the escape of gases therethrough, and by properly setting the dampers the desired amount of heat may be at all times furnished the sides of the boiler above the level 20 of material therein.

I claim:

1. In a still of the class described, a boiler, a setting in which the boiler is mounted, there being a heating chamber formed in the 25 setting below the boiler, the floor of said chamber being formed with openings therethrough, fireboxes movable through said openings, and means for supporting and moving said fireboxes through said openings.

2. In a still of the class described, a boiler, a setting on which the boiler is mounted, there being a heating chamber beneath the boiler in said setting the floor of which is 35 formed with openings therethrough, fireboxes extending into said openings, and means for independently raising and lowering the fireboxes.

3. In a still of the class described, a boiler, a setting on which the boiler is mounted, there being a heating chamber in the setting beneath the boiler in the floor of which openings are formed, a carrier for each firebox, a crosshead for engaging each carrier 45 and raising and lowering it with the firebox thereon, and means for reciprocating the crosshead.

4. In a still of the class described, a boiler, a setting on which the boiler is mounted, there being a heating chamber in the setting beneath the boiler and the floor of the heating chamber having openings therethrough, a firebox reciprocable in each opening, a carrier for the firebox, a hydraulic cylinder, and means operated by the hydraulic cylinder for raising and lowering the firebox.

5. In a still of the class described, a boiler, a setting on which the boiler is mounted, 60 there being a heating chamber in the setting below the boiler and openings through the floor of said chamber, a firebox reciprocable in each opening, means for raising and lowering the firebox, burners in the firebox, fuel supply pipes in the setting and flexible

connections between said supply pipes and burners.

6. In a still of the class described, a boiler, a setting on which the boiler is mounted, there being a heating chamber beneath the boiler in the setting, and openings in the floor of said chamber, a firebox movably mounted in each opening, means for moving the fireboxes, burners in each firebox, means for supplying the burners with fuel and checker work mounted on each firebox above the burners.

7. In a still of the class described, a boiler, a setting on which the boiler is mounted, independently movable fireboxes beneath the boiler and independent means for raising and lowering the respective fireboxes.

8. In a still of the class described, a boiler, a setting on which the boiler is mounted, there being a heating chamber in the setting beneath the boiler, the floor of the chamber having an opening therethrough, a firebox vertically movable through said opening, a carrier on which the firebox is mounted, means for engaging the carrier for raising and lowering the same with the firebox thereon, and a track beneath the heating chamber on which said firebox is movable when lowered thereon by said raising and lowering means.

9. A battery of stills of the class described, each still having a boiler, a setting on which the boiler is mounted, there being a heating chamber in the setting beneath the boiler, the floor of the chamber having an opening therein, a firebox, a wheeled carrier on which the firebox is mounted, means beneath said opening for raising and lowering said carrier with the firebox, tracks beneath the still adapted to receive the wheels of said carrier, a track extending along the battery of stills and a car on said track adapted to receive a carrier from the tracks of one still of the battery and to transport it to a position to engage the tracks of another still of the battery.

In testimony whereof, I have subscribed my name.

GEORGE W. KING.
